(57) **CLAIM**

The ornamental design for a table board, as shown and described.

DESCRIPTION

FIG. 1 is a front elevation view of a table board showing a first embodiment of the new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a perspective view thereof;

FIG. 8 is an enlarged rear elevation view showing a portion of the first embodiment taken from the encircled area 8 shown in FIG. 2;

FIG. 9 is an enlarged perspective view showing a portion of the first embodiment taken from the encircled area 8 shown in FIG. 2;

FIG. 10 is a front elevation view of the table board showing a second embodiment of the new design;

FIG. 11 is a rear elevation view thereof;

FIG. 12 is a left side elevation view thereof;

FIG. 13 is a right side elevation view thereof;

FIG. 14 is a top plan view thereof;

FIG. 15 is a bottom plan view thereof;

FIG. 16 is a perspective view thereof;

FIG. 17 is an enlarged rear elevation view showing a portion of the second embodiment taken from the encircled area 17 shown in FIG. 11; and,

FIG. 18 is an enlarged perspective view showing a portion of the second embodiment taken from the encircled area 17 shown in FIG. 11.

The broken lines shown in FIGS. 2, 8, 11, and 17 depict the limits of the enlarged views and form no part of the claimed design.

1 Claim, 18 Drawing Sheets
